UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR USE IN DECOMPOSING METALLIC SALTS AND DESULPHURIZING ORES.

SPECIFICATION forming part of Letters Patent No. 399,123, dated March 5, 1889.

Application filed January 3, 1889. Serial No. 295,369. (No model.)

To all whom it may concern:

Be it known that we, PHINEAS H. ADAMS, Jr., and ORSEMAS T. X. ADAMS, citizens of the United States, residing at Chicago, Illinois, have invented certain new and useful Improvements in Apparatus for Use in Decomposing Metallic Salts and Desulphurizing Ores, of which the following is a specification.

The object of our invention is to improve an apparatus for mechanically decomposing metallic salts and desulphurizing ores or their resulting material, when the substances treated are in a molten condition, by the action of centrifugal force; and our invention consists in the features and details of construction hereinafter described and claimed.

In the drawings, Figure 1 is a vertical longitudinal section with the running-gear in elevation. Fig. 2 is an end elevation of a detail on the line 2 2 of Fig. 1, looking in the direction of the arrows. Fig. 3 is an end elevation of a detail on the line 3 3 of Fig. 1, looking in the direction of the arrow; and Fig. 4 is a vertical longitudinal section of the receiving-vessel, with a furnace for supplying it with a heated blast.

In making our improved apparatus for decomposing chemical compounds, metallic salts, or salts of metals, and desulphurizing ores, we make a vessel, V, constructed and adapted to receive the substances to be treated when in a molten condition. This receiving-vessel may be made in such a way as will secure the required strength and reduce the conduction of heat from the interior to the exterior. It may be surrounded by a curbing and have a removable bottom or end to facilitate the removal of the material not thrown off by the action of centrifugal force, and in other respects it may be made as will be calculated to subserve the end in view and permit of its being rotated at a high rate of speed for the separation of particles of different degrees of density in the matter treated. Many of these parts and the details of their construction, as they do not form the special subject-matter of our present claims, need not be more fully described, as they will be sufficiently understood from an inspection of the drawings. The receiving-vessel, however, is intended to be rotated in a horizontal instead

of a vertical position, and therefore necessitates a special adaptation of various parts to this end, as hereinafter described.

An actuating-shaft, A, is arranged in horizontal journals or bearings supported in a suitable frame-work, which may be indicated by the letter B. This frame-work will, of course, be of a size and strength adequate to sustain the receiving-vessel with its heavy load of molten material. One of the journals, C, may be a plain bearing or box in which the outer portion of the actuating-shaft rests and revolves. The other bearing, D, however, we prefer to make in the form of a box adapted to receive a number of rollers or wheels, E, preferably journaled in suitable bearings in the sides of the box and affording just sufficient space in the center for the passage of the actuating-shaft, so that its surface will bear against the surface of the wheels or rollers. By this arrangement extreme or injurious friction will be prevented between the actuating-shaft and the bearing as it operates under the heavy load or strain to which it will be subjected, as hereinafter described.

The actuating-shaft is provided with a pulley or belt surface, F, connected with any convenient source of power, so as to rotate the actuating-shaft and the receiving-vessel to which it is attached. The inner end of the actuating-shaft is preferably provided with a collar, G, which is keyed or otherwise fixed to the actuating-shaft, so that it will rotate as it revolves. The end of the receiving-vessel opposite its mouth, through which the molten material to be treated is introduced, is preferably provided with an extension, H, of larger internal diameter than the mouth through which the molten material is introduced. The end of this extension is preferably made removable, so as to permit access to the receiving-vessel for any desired purpose, although we prefer, also, to make the receiving-vessel separable at the point of its largest diameter, I, as shown in the drawings. This will enable any material to be removed which is not thrown off by the action of centrifugal force. The end of the receiving-vessel, beyond the extension H, is preferably provided with a further extension, J, which surrounds or incloses the collar G on the inner end of

the actuating-shaft. These extensions H and J are separated from each other by the partition or end K of the extension H. The collar G is preferably provided with studs g, and coiled springs connect these studs with the inner sides of the extension J. This will be readily understood from an inspection of Fig. 2 of the drawings. A bolt or pin, L, passing loosely through the extension J and rigidly through the collar G and actuating-shaft A, serves to connect the parts together, and causes the receiving-vessel to rotate with the rotation of the actuating-shaft. The springs interposed between the collar G and the inner sides of the extension J form such a flexible or yieldable connection between the two that, while supporting or sustaining the weight of the receiving-vessel, they will permit sufficient play between the extension J and the collar G as to accommodate them to the vibrations of the receiving-vessel in operation without subjecting the actuating-shaft to that strain which would be occasioned were they rigidly united.

In order to further support the mouth end of the receiving-vessel, we prefer to provide it with a ring or collar, M, affording a belt-surface, surrounding the extending mouth of the receiving-vessel, with a small annular space between them. This ring or collar is preferably sustained by bolting it to a collar, N, provided with an inwardly-projecting flange to accommodate the location of a number of springs between it and the flange O, which extends from the case or wall of the receiving-vessel. These springs are shown in Figs. 1, 3, and 4, and they form a flexible or yieldable connection between the mouth end of the receiving-vessel and the ring or collar M, which is preferably sustained by a belt to a shaft, Q, as shown in Fig. 1. They permit the necessary play to accommodate the parts to the vibrations of the receiving-vessel when in use. These springs are indicated by the letter o.

We prefer to provide the extension H of the receiving-vessel with a number of holes, S, through which the material thrown off by the action of centrifugal force may be discharged. In making the extension H with an internal diameter somewhat larger than the internal diameter of the mouth of the receiving-vessel the material thrown off by the action of centrifugal force will be caused to be discharged at this end instead of at the mouth, while by making the diameter of the extension H considerably smaller than the internal diameter of the receiving-vessel an annular chamber or recess is provided around the outer edge of the receiving-vessel to catch and retain the heavier particles of the material being treated, while the lighter portion is driven through the receiving-vessel into the extension to the holes S, where it is discharged, as shown in Fig. 1. To catch the material discharged through the holes S and enable it to be properly carried away, we prefer that these

holes shall open into an annular chamber or trough, R, into which the material is discharged, and from which it flows through a 7c spout at the bottom to a car or other vessel, to permit it to be conveyed away.

In order to heat the interior of the receiving-vessel, or to prevent it from becoming cool when there is any interruption in the admission of molten material to be treated, we prefer to employ a furnace, T, with a pipe entering the mouth of the receiving-vessel, to admit of a hot blast being driven into such vessel. The production and application of 80 this heated blast by means of the furnace T differ in no material respects from the production and application of other heated blasts, and need not be minutely described in detail. This furnace may be omitted or modified, if 85 desired, as well as various other features illustrated in the drawings—as, for instance, the outer curbing and the means for conveying away the molten slag and other similar matters.

In order to counterbalance the weight of the receiving-vessel and its superimposed load exerted on one end of the actuating-shaft, we prefer to extend the other end of the actuating-shaft beyond the journal C, and 95 provide it with a pulley or belt, U, and connect it with a belt to a pulley or belt-surface, W, as shown in Fig. 1. By properly tightening the belt connecting those two pulleys, for which means are provided, as shown in Fig. 100 1, the outer end of the actuating-shaft may be prevented from bearing against the upper part of its bearing C with extreme or injurious friction. We have shown, also, in dotted lines another means for securing this same 105 end. This alternative means consists in the employment of a wheel or pulley, X, adapted to be adjusted so as to bear down upon the pulley U and prevent it from bearing upward, as above explained. This, however, 110 will be readily understood from the drawings.

In operation the molten material to be treated is introduced by a pipe or spout through the mouth of the receiving-vessel, which, if desired, may be only large enough 115 to permit this. Before the admission of material to be treated the receiving-vessel is preferably brought to a rotation of several thousand revolutions per minute. As the material falls into the receiving-vessel it will 120 instantly be acted upon, and the heavier particles of the material rapidly carried to the sides of the receiving-vessel. As new material flows in, and the annular space or chamber around the inner sides of the receiving-vessel fills up, the lighter particles constantly 125 coming to the inside and the heavier particles passing to the outside, the lighter particles will be driven by the action of centrifugal force through into the extension H, where 130 they will be forced out through the holes S and carried off, as above described. As soon as sufficient material has been introduced into the vessel to cause the lighter particles

to begin to be forced through the extension H and out through the holes S there will be a constant and uninterrupted discharge of the lighter particles of the material as long as the stream of molten material is flowing into the vessel through the mouth. The separation, of course, begins as soon as the material is deposited in the receiving-vessel near its mouth, and as it is driven along toward the other end of the vessel the separation becomes more and more perfect, until by the time of its discharge it is practically free from all of the heavier and more valuable particles. After the operation has been continued long enough

to secure a sufficient body of the heavier particles of the material around the sides of the receiving-vessel, the vessel may be stopped, and the body of heavier particles, still mostly in a molten condition, if desired, removed by opening the vessel at the end, or in any other convenient way. In this way the vessel may be operated again and again, with short intermissions for emptying the heavier particles which have accumulated around the sides.

What we regard as new, and desire to secure by Letters Patent, is—

1. In an apparatus for decomposing metallic salts or salts of metals and desulphurizing ores when in a molten state, the combination of a horizontal revoluble receiving - vessel adapted to receive molten material to be treated, and having a mouth at one end through which the molten material is introduced and an annular extension at the other, having its interior of less diameter than the interior of the receiving - vessel, containing one or more openings in its walls through which the material thrown off by the action of centrifugal force is discharged, a horizontal revoluble actuating-shaft rotating said vessel as it revolves, and means for rotating the actuating - shaft, substantially as described.

2. In an apparatus for decomposing metallic salts or salts of metals and desulphurizing ores when in a molten state, the combination of a horizontal revoluble receiving - vessel adapted to receive molten material to be treated, and having a mouth at one end

through which the molten material is introduced and an annular extension at the other, having its interior of less diameter than the interior of the receiving-vessel, closed at its outer end, and containing one or more openings in its walls through which the material thrown off by the action of centrifugal force is discharged, a horizontal revoluble actuating-shaft rotating said vessel as it revolves, a yieldable connection between the actuating-shaft and the receiving-vessel to accommodate the vibrations of the latter, and means for rotating the actuating-shaft, substantially as described.

3. In an apparatus for decomposing metallic salts or salts of metals and desulphurizing ores when in a molten state, the combination of a horizontal revoluble receiving - vessel adapted to receive molten material to be treated and having a mouth at one end through which the molten material is introduced, a horizontal revoluble actuating-shaft rotating said vessel as it revolves, a counter-balance device to counterbalance the weight of the receiving-vessel and its load, and means for rotating the actuating-shaft, substantially as described.

4. In an apparatus for decomposing metallic salts or salts of metals and desulphurizing ores when in a molten state, the combination of a horizontal revoluble receiving - vessel adapted to receive molten material to be treated and having a mouth at one end through which the molten material is introduced, a horizontal revoluble actuating-shaft rotating said vessel as it revolves, a bearing for the actuating-shaft, comprising a number of wheels or rollers bearing against the actuating-shaft and rotating as it rotates, a counter-balance device to counterbalance the weight of the receiving-vessel and its load, and means for rotating the actuating-shaft, substantially as described.
